UNITED STATES PATENT OFFICE.

FRÉDÉRIC DE COPPET, OF LAUSANNE, SWITZERLAND.

STAMP-CANCELING MACHINE.

1,092,561.

Specification of Letters Patent. Patented Apr. 7, 1914.

Application filed July 10, 1912. Serial No. 708,558.

To all whom it may concern:

Be it known that I, FRÉDÉRIC DE COPPET, engineer, a citizen of Switzerland, residing at Lausanne, Canton of Vaud, in the Con-

5 federation of Switzerland, have invented certain new and useful Improvements in Stamp-Canceling Machines, of which the following is a specification.

My invention relates to improvements in 10 and relating to stamp canceling machines.

The machine made in accordance with my 15 invention preferably comprises a die, an inking roller and devices adapted to permit an oscillating movement of the die as well as the inking roller and the parts are arranged and operated so as to take the ink from the surface of an ink pad and to automatically ink the surface of the die at each reciprocating movement of the device.

20 My improved machine is intended to be employed in the post offices and permits a rapid obliteration of letters and other matters.

The accompanying drawing illustrates by 25 way of example an embodiment of my invention.

Figure 1 is an elevation. Fig. 2 is a front view. Fig. 3 is a side view of the die on a somewhat enlarged scale. Fig. 4 is a detailed view showing the inking device of the die.

Similar letters refer to similar parts throughout the several views.

The machine as illustrated is adapted to 35 be driven by hand. It comprises a vertical support *a* with a base which is intended to be fixed on a table for receiving the objects to be canceled or obliterated. This sup-

port has two horizontal arms *a*¹ and *a*² at 40 the end of which two part crank-shaft *b* is pivoted. Pivoted on the cross bar *b*¹ of the same is a frame *c*, which carries the stamping device proper. This device comprises a vertical shaft *d* which is adapted

45 to slide vertically in the ends of two arms *c*¹ and *c*² of the frame *c*. A spring *e* tends to force the shaft *d* upwardly and normally to maintain it in its highest position. An arm *d*¹ is fixed on the shaft *d* and the free

50 end thereof is arranged to slide in a groove in a bar *c*³ of the frame *c*, to prevent the shaft *d* from rotating. The shaft *d* is provided at its lower end with a member *f* which carries a die *g* as shown in Figs. 1,

55 2 and 3, and a pin *h*' on which a connecting rod *h* is pivoted, which transmits the

movement imparted to the shaft *d* by means of a handle *i* to the elements which cause the inking of the printing surface of the die *g*.

An inking roller *j* is mounted on the ends of the branches of a fork *k* (Fig. 4), mounted on an arbor *m* which is parallel to the roller *j*. This arbor *m* is surrounded by a spring adapted to maintain the roller *j* 65 against the printing surface of the die *g*. The arbor *m* is carried by two arms *n*' and *n*² which are parallel to each other and fastened on an arbor *o*, which is parallel to the arbor *m* and is carried by a support *o*' which is fixed in a bracket secured to the frame *c*, and to this bracket is also connected the inking pad hereinafter described. The frame *c* is furthermore provided with an inking device consisting of a semi-circular 70 support piece *r* carrying an ink-pad *r*' on which the roller *j* may roll. The member *f* carries a device for holding in position the object to be stamped and this consists of a rod *q* adapted to slide in a sleeve *q*' and to 75 be pressed downwardly by a spring *q*².

The above described machine works in the following manner: The object *s* to be canceled or obliterated is placed in front of and beneath the die on a cushion or the 80 like provided on the table which carries the machine. The portion *i*' of the handle *i* is

taken for example between the forefinger and the middle finger of the left hand of the operator and by depressing the portion *i*² 85 the shaft *d* is moved downwardly until the die *g* strikes the object *s*. At the same time the connecting rod *h*, the arms *n*' and *n*² and therefore the arbor *m* and the fork *k* are also moved. In this movement, the roller *j* rolls 90

on the surface of the die *g* and inks the same until the surface of the die reaches the plane of the lower end of the ink pad *r*' of the inking device *r*. At this moment the roller 95

which is pulled by the arms *n*' and *n*² begins 100 to roll on the ink pad *r*' and inks itself. The roller is therefore positively drawn over the underside of the die during the descending movement of the same. Before the printing surface of the die reaches the object *s*, the

head of the rod *q* engages and presses on the object *s* and maintains it in place during the cancellation. After the object *s* has been 105 canceled or obliterated the spring *e* raises the shaft *d* and all the elements connected to it into their normal positions. A spring *t* prevents the top part of the member *f* from

- contacting with the arm c^2 . Owing to the double crank shaft b pivoted to the arms a^1 and a^2 of the support a it is possible to give to the die a horizontal swaying movement.
- 5 It is therefore easy to cancel several postage stamps affixed to a common piece of mail matter, without shifting the position of this matter but simply by displacing the frame c with the hand holding the handle i .
- 10 The die g which often must be removed in order to change the hours for instance, is provided as usual with a tail g^2 which enters the member f and is maintained in the same by means of a spring f' which may be controlled by a button f^2 . For removing the die g the shaft d is for instance pushed down until the roller j touches the ink-pad r' ; then the button f^2 is pressed and the die g is unlocked and falls out. After the double 15 pin u has been removed the disks of the die may be rotated so as to change the numbers indicating the date or hours.
- The fork h may oscillate on a pin l which is perpendicular to the axis of the roller, 20 the oscillating movements being limited by the branches of a small fork v . For this reason the roller always makes perfect contact both with the surface of the die to be inked or with the ink pad r' .
- 25 30 For removing the roller j , the screws j' and j^2 (Fig. 4) which are provided with a cylindrical hollow part j^3 through which passes the arbor of the roller, are unscrewed from slots in the ends of the fork h whereby the ends of the arbor of the roller are liberated and may be withdrawn from the slots. In an analogous manner the arbor o may be removed by unscrewing the screws o^2 which 35 also have a hollow cylindrical part, whereafter this arbor may be withdrawn from slots provided in the ends of the arms carrying it.

I claim as my invention:

1. A stamp canceling machine comprising a support, a two-part frame connected to the support to swing horizontally thereon, a shaft movable vertically in the said frame, a device detachably connected to the said shaft at the lower end thereof, a die connected to the said device, an inking pad secured to the said frame, a support carried by the said frame, a pair of spaced arms pivotally mounted on the said support, an arbor extending between the said arms, a pin fixed on the said arbor, a roller frame revolubly mounted on the said pin, an inking roller secured in the said roller frame, and means for connecting the said spaced arms to the said shaft so that the same and the inking roller are actuated by the movement of the shaft. 50

2. A stamp canceling machine comprising a support, a two-part frame connected to the support to swing horizontally thereon, a shaft movable vertically in the said frame, a device detachably connected to the said shaft at the lower end thereof, a die connected to the said device, an inking pad secured to the said frame, a support carried by the said frame, a pair of spaced arms pivotally mounted on the said support, an arbor 55 extending between the said arms, a pin fixed on the said arbor, a roller frame revolubly mounted on the said pin, an inking roller secured in the said roller frame, a pin fixed in the lower portion of the said shaft, and a 60 link connecting the last aforesaid pin with the said spaced arms. 70

In testimony whereof I have affixed my signature in presence of two witnesses.

FRÉDÉRIC DE COPPET.
